CLAIM

The ornamental design for a two component power take-off coupling system, as shown and described.

DESCRIPTION

FIG. 1 is a rear view of the first component of my two component power take-off coupling system;

FIG. 2 is a front view of the first component;

FIG. 3 side view of the second component of my two component power take-off coupling system;

FIG. 4 is a perspective view of the second component;

FIG. 5 side view of the first and second components attached together; and

FIG. 6 is a perspective view of the first and second components attached together.

FIG. 7 is an opposite side perspective view of the first and second components attached together as shown in FIG. 6; and,

FIG. 8 is an exploded perspective view of the first and second components showing how they fit together.
